US0D1052560S

(12) **United States Design Patent** (10) **Patent No.:** **US D1,052,560 S**
(45) **Date of Patent:** **** Nov. 26, 2024**

(54) **CASE WITH EARPHONES**

- (71) Applicant: **Apple Inc.**, Cupertino, CA (US)
- (72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)
- (73) Assignee: **Apple Inc.**, Cupertino, CA (US)
- (**) Term: **15 Years**
- (21) Appl. No.: **29/909,301**
- (22) Filed: **Aug. 3, 2023**

Related U.S. Application Data

- (63) Continuation of application No. 29/852,137, filed on Sep. 2, 2022, now Pat. No. Des. 994,645, which is a continuation of application No. 29/811,151, filed on Oct. 12, 2021, now Pat. No. Des. 962,643, which is a continuation of application No. 29/764,869, filed on Jan. 4, 2021, now Pat. No. Des. 933,636, which is a

continuation of application No. 29/706,555, filed on Sep. 20, 2019, now Pat. No. Des. 907,009.

CLAIM

The ornamental design for a case with earphones as shown and described.

DESCRIPTION

FIG. 1 is a front perspective view of a case with earphones showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the case with earphones that form no part of the claimed design.

1 Claim, 6 Drawing Sheets

FIG. 1

FIG. 2

FIG. 3

FIG. 4

FIG. 5

FIG. 6

FIG. 7
